The ornamental design for a fused safety power strip for Christmas tree lights, as shown and described.

DESCRIPTION

FIG. 1 is a front elevational view of the fused safety power strip for Christmas tree lights showing my new design;

FIG. 2 is a rear elevational view thereof;

FIG. 3 is a left side view thereof;

FIG. 4 is a right side view thereof;

FIG. 5 is a top plan view thereof; and,

FIG. 6 is a bottom plan view thereof.

In FIGS. 2, 5 and 6, the cord is shown broken away to indicate indeterminate length.
